UNITED STATES PATENT OFFICE.

ERNESTINE J. WILSON, OF BALTIMORE, MARYLAND.

DESIGN FOR A HAIR-FRAME.

SPECIFICATION forming part of Design No. 32,630, dated May 1, 1900.

Application filed March 21, 1900. Serial No. 9,621. Term of patent 7 years.

To all whom it may concern:

Be it known that I, ERNESTINE J. WILSON, a citizen of the United States of America, residing at Baltimore, in the State of Maryland, have invented a certain new and useful Design for a Hair-Frame, of which the following is a specification, reference being had therein to the accompanying drawings.

One object of this invention is to provide a new and original design for a hair-frame, and the leading feature resides in a central diamond-shaped portion provided with elongated ends, the outer edges of which are bound with fabric.

A further distinct feature resides in the transversely and diagonally arranged ribs, which form triangular spaces, one of which is covered with netting.

The details of construction will be apparent from the hereunto-annexed specification, reference being had to the accompanying drawings, forming part of this application, wherein—

Figure 1 is a view in perspective. Fig. 2 is a central transverse sectional view. Fig. 3 is a top plan view.

In the drawings, 1 indicates the transverse rib, which is made of metal and covered with

fabric. A longitudinal spring-rib 2 crosses the rib 1 below its center and at substantially 30 right angles thereto, said rib 2 being covered like rib 1 and having its ends elongated to form clasping members.

3 and 4 are diagonal covered spring-ribs, which cross each other and the transverse rib 35 at a point above the intersection of the ribs 1 and 2.

The entire frame is bound with fabrics 5 and 6, joined at the extreme ends of the rib 2. A triangular-shaped piece of netting 7 is 40 secured on the upper side of the frame.

My frame is designed to be used as a foundation for making hair structures, the hair being secured around the edges of the fabric to the ribs and in the netting. 45

What I claim as my invention is—

The design for a hair-frame as shown and described.

In testimony that I claim the foregoing as my own I have hereto affixed my signature in 50 the presence of two witnesses.

ERNESTINE J. WILSON.
